UNITED STATES PATENT OFFICE.

ALBERT ENNIS HENDERSON, OF TORONTO, CANADA, ASSIGNOR TO THE TORONTO ROLLER BEARING COMPANY, LIMITED, OF TORONTO, CANADA, A CORPORATION OF CANADA.

ROLLER-BEARING.

SPECIFICATION forming part of Letters Patent No. 718,122, dated January 13, 1903.

Application filed June 27, 1902. Serial No. 113,455. (No model.)

To all whom it may concern:

Be it known that I, ALBERT ENNIS HENDERSON, of the city of Toronto, in the county of York and Province of Ontario, Canada, have 5 invented certain new and useful Improvements in Roller-Bearings; and I hereby declare that the following is a full, clear, and exact description of the same.

This invention relates to certain new and 10 useful improvements in that class of roller-bearings in which the bearing-rollers are provided with bearing-rings held together by suitable tie-rods, and it relates more particularly to the peculiar construction of the tie-rods and the spacing-rollers mounted thereon to contact the bearing-rollers and hold them in parallel and concentric alinement.

In carrying out the invention I provide the tie-rods with journals for the spacing-rollers 20 mounted thereon and interpose spacing-washers between the inner faces of the retaining-rings and the shoulders of the journals to hold the retaining-rings properly spaced from each other and from the ends of the bearing- 25 rollers and so arranged that they will contact the ends of the spacing-rollers and prevent the longitudinal displacement of the same on the tie-rods.

In the drawings, Figure 1 is a perspective 30 view of a roller-bearing with one of the bearing-rings removed to show the relative position and the construction of the bearing-rollers, tie-rods, and spacing-rollers. Fig. 2 is a perspective view of one of the bearing-rings. 35 Fig. 3 is a sectional view of one of the spacing-rollers, tie-rods, and a portion of each of the bearing-rings. Figs. 4 and 5 are similar views of modifications shown in Fig. 3.

Like letters of reference refer to like parts 40 throughout the specification and drawings.

For an understanding of the present invention I have shown it applied to a specific form of roller-bearing; but I do not intend to confine the invention to this or to any other 45 specific form of bearing rings and rollers. Loosely mounted on the tie-rods d are the spacing-rollers e , of a lesser diameter than the bearing-rollers c and contacting therewith to hold the bearing-rollers properly spaced during their combined revolution with the bear-

ing-rings or their individual revolution therein. To reduce the frictional contact between the spacing-rollers and the tie-rods, the tie-rods are provided with journals f intermediate the ends, upon which are loosely mounted 55 the spacing-rollers e , the spacing-rollers contacting only with the journals.

As shown in Fig. 3 of the drawings, the shanks of the tie-rods are screw-threaded and pass through corresponding apertures g in 60 the bearing-rings, the shanks d' being fitted on the outer side of the bearing-rings with nuts h to prevent the outward displacement of the bearing rings and on the inner side of the bearing-rings with separable washers i , 65 bearing against the inner faces of the bearing-rings and the shoulders of the journals e to enable the tie-rods to hold the bearing-rings properly spaced. Said washers are of greater diameters than the journals, while 70 the journals are of greater diameters than the tie-rods.

As shown in Fig. 3, the tie-rod is fitted with a single spacing-roller to contact the adjacent bearing-rollers, the spacing-roller being located intermediate the ends of the tie-rod and of a sufficient length to form a substantial contact with the bearing-rollers and maintain them in their relative alinement, the spacing-rollers being prevented from moving longitudinally on the tie-rods by the washers i , abutting against the inner faces of the retaining-rings and the shoulders of the tie-rod journals, there being sufficient clearance between the ends of the spacing-rollers and washers to 85 allow of the free revolution of the spacing-rollers on the journal.

In Fig. 4 I form the tie-rod with the enlarged central portion or journal f' , which has mounted thereon the spacing-roller e' , 90 which is shorter in length than the journal. In this form I also dispense with the use of one nut, as h , by threading the opening in one of the bearing-rings to receive the threaded end g' of the tie-rod. Upon the tie-rod, 95 between the journal f' and the bearing-rings, are the long washers i' .

In Fig. 5 each tie-rod is shown to be fitted with two spacing-rollers e'' , loosely mounted on journals rotated in juxtaposition to the 100

tie-rod shanks, the inward displacement of the spacing-rollers being prevented by shoulders j on the tie-rods d'' and the outward displacement by the washers i'' , a sufficient clearance existing between the ends of each spacing-roller and its respective washer and shoulder to allow of the free revolution of the spacing-roller on its respective journal.

Having thus fully described my invention, what I claim as new, and desire to secure by Letters Patent, is—

1. In a roller-bearing, the combination of bearing-rollers, bearing-rings therefor, tie-rods for holding the bearing-rings relatively to the bearing-rollers, said tie-rods being provided with journals, spacing-rollers loosely mounted on the journals of the tie-rods to contact the bearing-rollers and having their ends within the ends of the bearing-rollers, and
- 20 means separably mounted upon the tie-rods and of greater diameter than the journals of the tie-rods and adapted to contact the shoulders of the journals and the inner side of the bearing-rings.

2. In a roller-bearing, the combination of 25 the bearing-rollers, bearing-rings therefor, tie-rods for holding the bearing-rings relatively to the bearing-rollers, there being journals on the tie-rods, spacing-rollers mounted on the journals and having their outer ends 30 within the ends of the bearing-rollers, and washers of greater diameters than the journals mounted upon the tie-rods to abut the shoulders of the journals and the inner faces of the bearing-rings.

3. In a roller-bearing, the combination of 35 the bearing-rollers, bearing-rings therefor, tie-rods for holding the bearing-rings together, spacing-rollers mounted on the tie-rods, abutting means for the inner faces of 40 the spacing-rollers, and washers at the outer ends of the spacing-rollers.

Toronto, June 18, A. D. 1902.

ALBERT ENNIS HENDERSON.

In presence of—

C. H. RICHES,
L. F. BROCK.
